his Atty.

UNITED STATES PATENT OFFICE.

J SHOWLES MACLEAN, OF TOLEDO, OHIO.

JAR RECEPTACLE.

Application filed May 18, 1928. Serial No. 278,846.

The jar receptacle is both ornamental and useful. While not exclusively confined thereto, it is especially adapted to receive and conceal an ordinary milk jar of the type now commonly in use. The jar will preferably be seated in the receptacle in such a way as to entirely enclose and conceal the jar and at the same time hold it more or less firmly in place in the receptacle so that liquid may be poured from the jar by manipulating the receptacle itself.

In the accompanying drawings Figure 1 is a side elevation of one form the device may take. Fig. 2 is a vertical, transverse section through the structure shown in Fig. 1, and Fig. 3 is a vertical, transverse section in a direction at an angle of the section shown in Fig. 2.

A base member 1 is provided with a spring 2 on which may rest the jar 3. Over this may be placed the main frame 4 of the receptacle and the whole may be locked in place by means of bayonet joints 5. These bayonet joints are placed toward the bottom of the device and may be made small and inconspicuous. At its upper portion the walls 4 may be turned inward slightly as at 6, and beneath the in-turned portions may be seated a gasket 7 which may be of a non-rigid material. By this means the spring 2 will hold the jar 3 more or less firmly in place and press the mouth of the jar 3 against the gasket 7. For convenience and beauty the walls 4 are made frusto-conical, tapering from the top to the bottom. If desired the portion toward the bottom which is engaged by the base member 1 may be made vertical to receive the vertical side walls of the base member 1.

The shape disclosed is well adapted to conceal the fact that a jar or bottle is within the casing, as well as to conceal the contents of the jar from view. This particular shape, however, is not essential, and any suitable or desired shape may be used. The spring and gasket allow the receptacle to adapt itself to variations in jar dimensions.

A spout 8 attached to the main wall 4 serves for a convenient means of delivery of the fluid from the jar, and may be the only portion of the device reached by the fluid in its travel from the jar. A handle 9 is provided by which the device may be handled for carrying or pouring. At the upper portion of the handle 9 is a lug 10 provided with a hole or indentations 11 on both

sides, from which may lead channels 12. A cover 13 is provided having a flat surface 14 to normally engage the in-turned annulus 6 when the cover 13 is held in its normal position. Resilient wings 15 project from the cover and are provided with inset portions or pins 16. The wings 15 may inclose the lug 10, there being one wing on each side and the inset portions or pins 16 may be inserted in the channels 12 and the resiliency in the wings will allow the device to be adjusted so that the pins 16 engage the openings 11. Thus the cover may be detachably pivoted to the receptacle. A thumb piece 17 extends from the cover 13 to a position conveniently adjacent the handle 9 so that the cover may be manipulated by the thumb of the hand which holds the handle 9. The side 14 of the cover being large and smooth makes a suitable closure for the device under normal circumstances, but need not absolutely seal against leakage. Through the resiliency of the wing members 15 the cover 13 may be detached from the receptacle and inverted as illustrated in Fig. 3 in which position it will be seen that the projection 18 on the cover 13 engages the mouth of the jar and seals it. This arrangement may be especially convenient if it is desired to shake the liquid in the jar before pouring it. The liquid may be shaken with the cover in the position shown in Fig. 3 and the cover may be returned to the position shown in Figs. 1 and 2 for delivery or distribution of the contents.

The specified details shown in the drawing are illustrative only and are not intended to limit the invention which may be embodied in other details. The term jar is used in a generic sense and may be taken to include containers of various shapes.

I claim as my invention:

1. A jar receptacle comprising a casing, a spring on which the jar is adapted to rest, a support for the spring removably attached to the casing by bayonet joints, a gasket in the casing against which the mouth of the jar is adapted to be held by the spring, a handle attached to the casing, a spout integral with the casing, a cover for the jar and the receptacle removably pivoted on the casing near the handle, a thumb piece on the cover adjacent the handle for manipulating the cover, and a projection on the cover which may enter and close the jar when the cover is not pivoted to the receptacle.

2. A jar receptacle comprising a casing, a spring on which the jar is adapted to rest, a support for the spring removably attached to the casing by bayonet joints, a gasket in the casing against which the mouth of the jar is adapted to be held by the spring, a handle attached to the receptacle, a spout integral with the casing, a cover for the jar and the receptacle, a lug on the casing near the handle, resilient members on the cover, upset portions on the resilient members adapted to engage holes in the lug, a thumb piece on the cover adjacent the handle for manipulating the cover, and a projection on the cover which may enter and close the jar when the cover is detached from the receptacle.

3. A jar receptacle comprising a casing, a spring in the receptacle on which a jar may rest, a lug on the casing, a cover having a flat surface engaging the mouth of the receptacle, resilient extensions on the cover adapted to engage the lug, and a projection on the cover which may enter and close the jar when the cover is released from the lug.

4. A jar receptacle comprising a casing, a lug on the receptacle, a cover for the jar having a flat surface engaging the mouth of the receptacle, resilient extensions on the cover adapted to enclose the lug, pins on the resilient members adapted to engage holes in the lug, and a projection on the cover which may enter and close the jar when the pins are released from the holes in the lug.

35 5. A jar receptacle comprising a casing,

a spring on which a jar is adapted to rest, a support for the spring removably attached to the casing by bayonet joints, a gasket in the casing against which the mouth of the jar may be held by the spring, a spout integral with the receptacle, a handle for the receptacle, a lug on the receptacle near the handle, a cover for the jar and receptacle, a thumb piece on the cover, resilient members on the cover adjacent the thumb piece, pins on the resilient members adapted to engage holes in the lug to pivot the cover so that the cover may be manipulated by the thumb piece near the handle, and a projection on the cover which may enter and close the jar after the pins are released from the holes in the lug.

6. A jar receptacle comprising a cover detachably pivoted to the receptacle and having a flat side, and a projection on the cover adapted to engage and close the mouth of a jar in the receptacle when the cover is detached from the receptacle.

7. A jar receptacle comprising a casing, a spring on which the jar is adapted to rest, a support for the spring removably attached to the casing, a gasket in the casing against which the jar is adapted to be held by the spring, a cover for the jar and the receptacle removably pivoted to the receptacle, and a projection on the cover which is adapted to enter and close the jar when the cover is not pivoted to the receptacle.

J SHOWLES MacLEAN.
